UNITED STATES PATENT OFFICE.

JOHN S. POWERS, OF NEW BURLINGTON, INDIANA.

WATER-GATE.

SPECIFICATION forming part of Letters Patent No. 244,664, dated July 19, 1881.

Application filed April 26, 1881. (No model.)

To all whom it may concern:

Be it known that I, JOHN SANTON POWERS, of New Burlington, in the county of Delaware and State of Indiana, have invented new Improvements in Water-Gates, of which the following is a full, clear, and exact description.

Figure 1 is a perspective view of my improvement. Fig. 2 is a side elevation of the same.

10 The object of this invention is to promote the efficiency of water-gates, increase their durability, and lessen their liability to get out of order.

15 The invention consists in constructing a water-gate of a base-frame secured to the bottom of the stream, an inclined frame hinged at its upstream end to the base-frame, and supported at its downstream end by hinged standards having a cross-bar attached to their upper 20 ends, and wheels pivoted to their lower ends, and the stops attached to the base-frame for the wheels of the supporting-standards to rest against, whereby the passage of animals will be prevented and the gate will be lowered to 25 the bottom of the stream by a rise of water or an accumulation of rubbish, as will be herein-after fully described.

30 A are the bed pieces or sills, which are placed longitudinally with the stream, and are secured in place by stakes, stones, or other suitable means. The sills A are connected at their ends by cross-pieces B, to keep the said sills in proper relative positions. The base-frame A B can be made of any desired size; 35 or, in the case of wide streams, it can be made in sections or parts.

40 At or near the inner edge of the upstream cross-piece B is placed a bar, C, the ends of which, or tenons formed upon the said ends, work in bearings attached to the sills A.

45 To the bar C are attached the ends of parallel bars D, which, at a little distance from their other ends, are attached to a cross-bar, E, forming a hinged frame, C D E. The ends of the cross-bar E, or tenons formed upon the said ends, work in bearings attached to two upright bars or standards, F.

50 To the lower sides of the lower ends of the standards F are pivoted small wheels G, which rest and roll upon the upper sides of the sills A.

To the sills A are attached stops H, for the wheels G to rest against, to prevent the lower ends of the standards F from passing down

too far. The stops H should be placed in such a position that the upper ends of the standards F will incline slightly upstream when the wheels G rest against the said stops H, so that the bars D will be firmly supported in an inclined position, as shown in Fig. 2. The upper ends of the standards F rise above the inclined bars D, and are connected by a cross-bar, I, as shown in Fig. 1.

With this construction the inclined bars D prevent animals from passing in either direction, and rubbish floating downstream can slide up the inclined bars D and pass off their upper or downstream ends. Should there be a rise of water, or should rubbish accumulate upon the bars D, the pressure against the upper ends of the standards F, or against the cross-bar I, will press the upper end of the said standards downstream, causing the wheels G to roll up the sills A, and allowing the bars D and standards F to drop to the bottom of the stream, so that the water and rubbish can pass on unobstructed. In some cases the standards F need not project above the bars D. The cross-bar I, the wheels G, and the stops H can be omitted, and the lower ends of the standards F permanently attached to the sills A, forming a stationary gate; but for ordinary purposes the construction first described is preferable.

Having thus described my invention, what I claim as new, and desire to secure by Letters Patent, is—

1. A water-gate constructed substantially as herein shown and described, consisting of the base-frame A B, the hinged frame C D E, the hinged supporting-frame F I, having wheels G, and the stops H, as set forth.

2. In a water-gate, the combination, with the base-frame A B and the hinged frame C D E, of the hinged supporting-standards F, having a cross-bar, I, attached to their projecting upper ends, and wheels G, pivoted to their lower ends, and the stops H, substantially as herein shown and described, whereby the hinged frame will be lowered by a rise of water or an accumulation of rubbish, as set forth.

JOHN SANTON POWERS.
